UNITED STATES PATENT OFFICE

ANDRE J. MEYER, OF DETROIT, MICHIGAN, ASSIGNOR TO CONTINENTAL MOTORS CORPORATION, OF DETROIT, MICHIGAN, A CORPORATION OF VIRGINIA

ENGINE

Application filed June 8, 1931. Serial No. 542,723.

This invention relates to internal combustion engines and has particular reference to improvements materially reducing the cost of manufacture and also improving the performance and wearing characteristics of the engine.

My said invention has particular reference to engines of the sleeve valve type although it will be apparent from my disclosure that my improvements will not necessarily be limited to this type of engine. For purposes of disclosure I have illustrated my improvements embodied in a sleeve valve engine of the type wherein a valve operating shaft is located in the crankcase structure of the engine since it is in connection with this general type of engine that my improvements are of particular importance. In such engines it is customary to provide a driving connection between the sleeve or sleeves and the valve operating shaft and it is very desirable to position the valve operating shaft as closely as possible to the axis of the sleeve or cylinder, since this results in a number of advantages. First of all, such positioning reduces the angle of thrust from the valve operating shaft to the sleeve whereby the sleeve may be operated more efficiently and the parts constituting the valve gear may be made lighter and cheaper. Secondly, such positioning reduces the over-all dimensions of the engine with a consequent saving in material and cost of production.

I attain the above objects by providing a novel construction for the connection between the piston connecting rod and the engine crankshaft by reason of which the connecting rod bearing cap is offset to provide an additional clearance over conventional constructions on the side of the engine containing the valve operating shaft. This additional clearance in my invention is occupied by the valve operating shaft which is thereby moved closer to the sleeve axis than would be otherwise possible.

Further objects and advantages of my invention reside in the novel combination and arrangement of parts more particularly hereinafter referred to. In the drawings:

Fig. 1 is a sectional elevation view through the engine illustrating my improvements.

Fig. 2 is a detail plan view of the engine shown in Fig. 1; and

Fig. 3 is a diagrammatic sectional elevation illustrating the additional clearance space provided for the valve operating shaft over the conventional arrangement of connecting rod bearing caps.

Referring to the drawings, reference character A represents the engine cylinder block providing the usual longitudinally spaced cylinders 10 closed by a suitable cylinder head structure 11, 12 and 13 representing intake and exhaust manifolds respectively. Each cylinder is provided with the usual intake and exhaust ports 14 and 15 respectively, these ports being controlled by suitable sleeve valve means. In the illustrated embodiment the engine is the Burt-McCollum type in which a single sleeve valve 16 is given a combined axial reciprocation and oscillation, whereby any point on the sleeve traces a closed curve path in accomplishing the usual porting of sleeve intake and exhaust ports 17 and 18 respectively with the associated cylinder intake and exhaust ports 14 and 15 respectively. Within the sleeve is located the usual piston 19 connected to the crank 20 of crankshaft 21 through the intermediary of a connecting rod 22.

This connecting rod 22 is provided with a bearing portion 23 and the associated bearing cap 24, which parts cooperate to surround the crank 20 to provide an operative bearing between the connecting rod and crank. The bearing cap 24 is offset preferably for the most part toward that side of the plane longitudinally of the engine containing the connecting rod axis X—X which is opposite the valve operating shaft 25. In order to provide such construction the bearing portion 23 is faced at 26 and 27, these faces lying in a plane out of perpendicular with the connecting rod axis X—X as shown in Fig. 1. The bearing cap 24 is provided with corresponding faces and the bearing portions 23 and 24 are secured together by suitable fastening bolt and nut assemblies 28 and 29.

Referring to the valve shaft 25 and asso-

ciated parts, the illustrated construction embodies a valve shaft provided with a wobble crank 30 associated with each sleeve valve, each wobble crank 30 comprising spaced ball portions 31 and 32 adapted to be engaged by the spaced socket portions 33 and 34 of a forked sleeve connecting rod 35. The latter rod is suitably connected by a ball and socket structure 36 with the associated sleeve valve 16 whereby the latter will be operated as aforesaid from the wobble crank 30. For the four-stroke cycle engine illustrated it will be readily understood that the valve shaft 25 is operated at one-half crankshaft speed and is adapted to be driven from the crankshaft by the usual driving mechanism not illustrated in this instance to avoid confusion.

Referring to Fig. 1, the line Y—Y represents the innermost path traveled by the wobble crank and associated mechanism during a cycle of its operation. The line Z—Z represents the outermost path defined by the travel of the connecting rod 22 and associated parts during a cycle of its travel. It will be noted that the lines Y—Y and Z—Z do not overlap whereby it will be readily understood that no interference will result during the operation of the engine and that by reason of my invention the line Z—Z occupies a position closer to the axis of the sleeve valve than it would save for the offset bearing cap 24. The additional space provided by the advantageous location of the line Z—Z has been occupied in my illustrated embodiment by correspondingly moving the valve shaft 25 toward the sleeve axis for an amount substantially equal to the extra clearance so afforded.

In order to further illustrate the clearance afforded by the offset construction, I have shown in Fig. 3 a diagrammatic representation of the critical outline traced by the connecting rod embodied in my invention, and also an outline of the critical point traced by conventional connecting rod assemblies. Thus in Fig. 3 the lines Y—Y and Z—Z are illustrated as in Fig. 1 and I have also illustrated in dotted lines the line Z'—Z' which would be traced by the outermost point of the connecting rod if the latter were constructed along conventional lines including the bearing portion 23', bearing cap 24', fastening devices 28' and the bearing faces 26' and 27', the latter in this instance lying perpendicular to the connecting rod axis. From this illustration it will be apparent that the valve operating shaft 25 could not occupy the position shown in Fig. 3 in combination with the bearing cap 24' since the line Z'—Z' overlaps the line Y—Y which would result in interference during engine operation between the associated parts of the wobble crank mechanism and the connecting rod.

While I have described and illustrated a specific type of valve shaft and operating

mechanism associated therewith, I desire it understood that my invention in its broader aspects is equally applicable to other types of valve shaft constructions as will be readily apparent from my disclosure.

What I claim as my invention is:

1. In an internal combustion engine, the combination of a cylinder, a piston, sleeve valve means arranged to have both axial reciprocation and circumferential oscillation, a crankshaft, a connecting rod intermediate the piston and crankshaft, a bearing cap for the connecting rod at its connection with the crankshaft, a valve operating shaft parallel to the crank-shaft, said valve operating shaft having a wobble crank, an operating connection between the wobble crank and said sleeve valve means, said bearing cap being offset for the most part to that side of the plane extending longitudinally of the engine containing the connecting rod axis opposite to the valve operating shaft, said valve operating shaft being closer to the cylinder axis than it could be save for such offset. 70

2. In an internal combustion engine, the combination of a cylinder, a piston, a crank-shaft, a connecting rod between the piston and crankshaft, a bearing cap for the connecting rod, said bearing cap being offset from the connecting rod axis transversely of the engine, valve means for the engine, a valve operating shaft for said valve means, said valve operating shaft extending parallel with the crankshaft to the side thereof opposite said offset whereby said valve operating shaft is positioned closer to the cylinder axis than it could be save for such offset. 90

3. In an internal combustion engine, the combination of a cylinder, a piston, a crank-shaft, a connecting rod between the piston and crankshaft, valve means for the engine, a valve operating shaft parallel with the crankshaft operating said valve means, means connecting the connecting rod with the crankshaft, said connecting means being offset to that side of the plane extending longitudinally of the engine containing the connecting rod axis opposite to the valve operating shaft, said valve operating shaft being closer to the crankshaft than it could be save for such offset. 105

4. In an internal combustion engine, the combination of a cylinder, a piston, a crank-shaft, a connecting rod between the piston and crankshaft, sleeve valve means associated with the cylinder, a sleeve valve operating shaft parallel with the crankshaft for actuating said sleeve valve means, means connecting the connecting rod with the crankshaft, said connecting means being offset to that side of the plane extending longitudinally of the engine containing the connecting rod axis opposite to the sleeve valve operating shaft, said sleeve valve operating shaft being located relatively close to said crankshaft 120

without interference therewith by reason of said offset connecting means.

5. In an internal combustion engine, the combination of a cylinder, a piston, a crank-shaft, a connecting rod between the piston and crankshaft, sleeve valve means associated with the cylinder, a sleeve valve operating shaft parallel with the crankshaft for actuating said sleeve valve means, means connecting the connecting rod with the crank-shaft, said connecting means being offset to that side of the plane extending longitudinally of the engine containing the connecting rod axis opposite to the sleeve valve operating shaft, said sleeve valve operating shaft being located relatively close to said crankshaft without interference therewith by reason of said offset connecting means, and a wobble crank carried by said sleeve valve operating shaft, said wobble crank being located to one side of and adjacent to the path of movement of said connecting rod connecting means.

6. In an internal combustion engine, the combination of a cylinder, a piston, a crank-shaft, a connecting rod between the piston and crankshaft, sleeve valve means associated with the cylinder, a sleeve valve operating shaft parallel with the crankshaft for actuating said sleeve valve means, means connecting the connecting rod with the crankshaft, said connecting means including a crankshaft engaging bearing cap faced for engagement with the connecting rod, said face lying substantially in a plane out of perpendicular with the connecting rod axis whereby said bearing cap is offset with respect to the connecting rod axis away from said sleeve valve operating shaft, said sleeve valve operating shaft being located relatively close to said crankshaft without interference therewith by reason of said offset bearing cap.

7. In an internal combustion engine, the combination of a cylinder, a piston, a crank-shaft, a connecting rod between the piston and crankshaft, sleeve valve means associated with the cylinder, a sleeve valve operating shaft parallel with the crankshaft for actuating said sleeve valve means, means connecting the connecting rod with the crankshaft, said connecting means including a crankshaft engaging bearing cap faced for engagement with the connecting rod, said face lying substantially in a plane out of perpendicular with the connecting rod axis whereby said bearing cap is offset with respect to the connecting rod axis away from said sleeve valve operating shaft, said sleeve valve operating shaft being located relatively close to said crankshaft without interference therewith by reason of said offset bearing cap, and a wobble crank carried by said sleeve valve operating shaft, said wobble crank being located to one side of and adjacent to the

path of movement of said connecting rod connecting means.

8. In an engine, a crankshaft having a crank, a piston, a connecting rod between the piston and crank, a bearing cap engaging the crank for securing the connecting rod to the crank, said bearing cap being offset in the plane of crank rotation relative to the longitudinal axis of the connecting rod, and a valve shaft adjacent said crankshaft at the side of said connecting rod opposite to said offset bearing cap, said valve shaft being located relatively close to the path of movement of said crank without interference therewith by reason of said offset.

9. In an engine, a crankshaft having a crank, a piston, a connecting rod between the piston and crank, a bearing cap engaging the crank for securing the connecting rod to the crank, said bearing cap being offset in the plane of crank rotation relative to the longitudinal axis of the connecting rod, and a valve shaft adjacent said crankshaft at the side of said connecting rod opposite to said offset bearing cap, said valve shaft being located relatively close to the path of movement of said crank without interference therewith by reason of said offset, said valve shaft having a wobble crank movable in the general plane of movement of said crank.

In testimony whereof I affix my signature.
ANDRE J. MEYER.
